Application October 15, 1943, Serial No. 506,322
In Great Britain December 15, 1942

Section 1, Public Law 690, August 8, 1946.
Patent expires December 15, 1962

12 Claims. (Cl. 179—16)

1

This invention relates to an arrangement for receiving and regenerating electric impulses and has for its object to provide a circuit arrangement by means of which signals consisting of impulses of uncertain duration and divided into trains of impulses with a minimum interval between such trains may correctly operate apparatus for registering such impulses.

According to one feature of the invention an arrangement for receiving and regenerating electric impulses comprises an impulse responding relay, a second relay the response of which is dependent upon the impulse responding relay and is timed by means of a condenser connected in its circuit and means for maintaining said impulse responding relay in the condition caused by a received impulse until the completion of response of said second relay.

According to a further feature of the invention an arrangement for receiving electric impulses and for timing a pause between trains of impulses comprises a relay the response of which is dependent upon the impulse responding relay and is timed for release and re-energisation in a self-interrupting circuit by means of a condenser connected in its circuit, means for releasing said relay for self-interruption during a pause between trains of impulses, and means controlled by the release and re-operation of said relay to time said pause and discriminate between such pause and the cessation of impulsing.

The invention will be better understood from the following description of one embodiment thereof taken in conjunction with the accompanying drawings in which Fig. 1 and Fig. 2 are two alternative circuits for a substation in an electric signalling system.

Referring to the drawings and first more particularly to Fig. 1, signals from a transmitter will be received by a plurality of substations each arranged after the manner shown in the drawing, each substation being connected over a line L to a common circuit. This circuit may be a party line or it may be that the messages are sent by radio to a plurality of stations each tuned to the same frequency. The impulses consist of interruptions of an alternating current which is rectified and applied to the control electrode of a three electrode gas-filled tube T. The arrange-

2

ment is such that normally no alternating current is being received. The receipt of alternating current indicates that a message is about to be sent and the received alternating current when rectified fires the tube T and operates the relay C. The circuit is then automatically changed so that the discharge in the tube T is extinguished and subsequently a cessation of alternating current constituting an impulse causes a discharge in the tube T. Received impulses will step the selector switch SR shown which is stepped by a magnet SRM and has five wipers and five banks of contacts. The first three trains of impulses constitute a station selecting code and the total number of impulses in these three trains is a constant total of 11. Subsequent trains of impulses cause the selector switch to be stepped two steps for each successive train of impulses. At the station for which the message is intended the successive trains of impulses are routed to the wires NIA—NIF. To each of these wires is connected a number indicator of the kind in which a rotating selector switch or other device is stepped by a sequence of impulses. The magnets of all the indicators are connected to a common terminal H to which ground is applied from the circuit shown in the drawing when it is desired to operate the indicator and to keep it operated. If the correct station code is not received, the selector switch will be stepped as stated above, but the trains of impulses are not routed to the wires NIA—NIF. Any message set up on the number indicators remains until the station code is again received, when it is cancelled and a further message set up.

The operation of the circuit shown will now be described in detail. The line L is connected to the primary of a transformer TR, the secondary of which is tuned to the desired frequency. In the drawing all relays except ED are shown in their unoperated condition. In the normal condition of the circuit it will be observed that there is a circuit for the relay ED from ground over back contacts ss¹, lower winding of relay ED, home contact and wiper of bank 1 of the switch, switch magnet SRM and negative battery. The current in this circuit is insufficient to operate the magnet SRM, but the relay ED is operated therein. Contacts ed¹ prepare a circuit for relay

C. When alternating current is received over the transformer TR it is rectified by the rectifier RA and applied over back contacts s_2 and resistances R_2 to the control electrode of a tube T and assists a positive potential of 40 volts connected to the back contacts s_1 . This tube is a cold cathode gas-filled tube having three electrodes to one of which (the anode) a potential of approximately 150 v.+ is applied. The other two electrodes are similar and either of them functions as the cathode or the control electrode. The electrode to which the rectified alternating current is applied will be hereafter called the control electrode and the other the cathode. Normally the cathode is connected over contacts s_3 back, ed_1 front, winding of relay C to ground, and when rectified alternating current is applied to the control electrode a discharge is initiated in the tube T, current flows through the winding of relay C and that relay operates. At front contacts c_1 , a circuit is closed for relay P (negative, winding of P, ed_2 front, ss_2 back, c_1 front, ground) which operates. Relay S operates over its lower winding to contacts p_1 front and ground, and at contacts s_4 front closes a circuit to operate relay SS over s_4 front, p_1 front and ground. Contacts s_3 open and remove potential from the cathode of tube T whereupon the discharge in the tube T is extinguished and relay C releases. At contacts s_1 and s_2 the potential of 40 v. previously applied to the control electrode of tube T is removed and potential of 80 v. is applied in opposition to the received rectified current from contacts s_2 , resistance R_1 , front contacts s_1 . At contacts c_1 the original operating circuit for relay P is opened but this relay locks over p_2 front and c_1 back. When relay P was first operated it closed a circuit for relay Y at contacts p_3 front and it operates. When relay C releases a circuit is closed for relay X over c_2 back and ss_1 front and it operates. At contacts x_1 front, relay G is operated and at contacts g_1 closes a circuit which holds relays S and SS operated independently of relay P. The operating circuit for relay ED is opened at contacts ss_1 and this relay releases. An alternative energising circuit for relay C is prepared at front contacts ss_6 and front contact g_2 . At contacts ss_5 ground is applied to a wire BL to indicate that current is being received.

When impulsing commences the impulses take the form of brief interruptions of the alternating current and when the alternating current ceases the potential of 80 v. applied to the control electrode of tube T is sufficient to initiate a discharge in the tube and operate relay C. The discharge once initiated remains, and relay C remains operated, even when the impulse comes to an end. A circuit for magnet SRM is closed over front contacts c_1 , front contact ss_2 , back contacts z_1 , magnet SRM and battery, and this magnet energises. At contacts c_1 the circuit of relay P is broken and that relay releases. At contacts c_2 the circuit for relay X is broken. This relay is maintained energised because of the condenser connected to its second winding for approximately 40 ms. before it releases. When relay X has released contacts x_2 connect a condenser CA (which has been discharged to ground through contact x_2 front) to the anode of tube T and cause the potential of the anode to be thus reduced sufficiently to extinguish the discharge in tube T, provided that the incoming impulse has ceased and alternating current is once more being received. Relay C releases and contacts c_1 break

5 the circuit of the magnet SRM which thereupon steps its wiper to the next set of contacts. Contacts c_2 reclose the circuit for relay X which re-operates after a further 40 ms. It will be seen that the impulses which are received are regenerated and the length of the impulses applied to the magnet SRM is independent of the length of the incoming impulses and depends mainly on the release time of relay X.

10 In the embodiment described the release of relay X brings the impulse to an end but it will be understood that relay X could be normally de-energised, its circuit closed on the receipt of an impulse and serve by this operation instead of by its release to bring the regenerated impulse to an end.

15 The above described changes take place at each received impulse, the switch SR stepping its brushes each time. Relay Y is kept operated during impulsive either over c_2 front and ss_1 front, or over ss_3 front and x_1 back. At the end of a digit one interruption of incoming current is omitted as an interdigital signal. When relay X has reoperated after the previous interruption, if the tube T is not again ignited, and relay C again operated, the circuits for relay Y are interrupted and relay Y releases after about 40 milliseconds. Its circuit is immediately reclosed over y_1 back, ed_3 back. Relay Y will re-operate again after about another 40 milliseconds.

20 A single release and re-operation of relay Y serves to indicate an interdigital pause. During the period of relay Y back a test is made as to whether the code is for the station shown. Contacts No. 1 to 10 in bank 3 of the selector switch are connectable by removable links to relay W, certain of these links being omitted in accordance with the station code. The code of the station shown is 452 and the links for contacts Nos. 4 and 9 (4+5) are removed. If the selector switch has, after the first train of impulses come to rest on any other contact than No. 4, a circuit is completed, whilst relay Y is back, from ground, c_1 back, p_2 back, y_2 back, ss_4 front, wiper and contact of bank 3 of the switch, relay W, battery. Relay W operates and closes a locking circuit for itself over w_1 front to g_1 front and ground. Operation of relay W prevents any message being transmitted to the number indicators as will be clear from the description hereinafter.

25 The second and third trains of impulses are received in the same manner as the first and the magnet SRM operated and released to step the wipers of the switch in the same manner as before. During the second interdigital pause, a circuit for relay W is again completed and if relay W has not previously operated and the switch has come to rest on a contact other than No. 9, relay W will be operated this time. If, however, the selector switch shown comes to rest on contact No. 4 after the first train of impulses and on contact No. 9 after the second train of impulses, relay W remains unoperated.

30 If a correct code be received, a total of eleven impulses will be received in three trains of impulses and the selector switch wipers will come to rest on contact No. 11. When Y releases during the interdigital pause following, a circuit is completed for relay Z, from ground, c_1 back, p_2 back, y_2 back, ss_4 front, contact No. 11 in No. 3 bank, rectifier MRA, z_1 back, winding of Z, negative battery. Relay Z operates and locks over z_2 front, rectifier MRB, g_1 front, ground.

35 At contacts z_1 relay Z disconnects magnet SRM from the original impulsive circuit and connects

relay AX in its place. At contacts $z3$ a circuit is completed for a calling lamp to wire CL. After the station identification code, a digit 0, represented by some predetermined number of impulses, is sent. Relay AX responds to the impulses, in a circuit over $z1$ front, $ss2$ front, $c1$ front. On the first operation of relay AX, relay ZA operates over contact No. 11 of bank 5 of switch SR, $ax1$ front, ground, and locks over $za2$ front, rectifier MRE, $g1$ front, ground. Other operations of AX have no effect at this time.

When the interpolated digit 0 ends, relay Y releases during the interdigital pause and a circuit is completed for relay ZB over $za1$ front, rectifier MRA, contact 11 of bank 3 of switch SR and wiper 3 , $ss4$ front, $y2$ back, $p2$ back, $c1$ back. ZB operates and locks over $zb1$ front, $z4$ front. A circuit is completed for magnet SRM over $za4$ front, contact and wiper of bank 4 of switch SR, $ss4$ front, $y2$ back, $p2$ back, $c1$ back, and when Y re-operates, magnet SRM steps the wipers of the switch on to contacts No. 12 .

When the next digit is received relay AX responds to the impulses, contacts $ax2$ repeat the impulses over $zb2$ front and $w2$ back, contact 12 of bank 2 to wire NIA and to a number indicator. A circuit for holding all the number indicators is completed over $w3$ back, $zb3$ front to wire H. It will be seen that if relay W had previously operated, these circuits would not be completed and thus no message impulses are recorded at a station for which they are not intended.

On the first operation of relay AX, contacts $ax1$ complete a circuit over contact No. 12 of bank 5 for magnet SRM and when relay AX de-energises, the wipers step to contact 13 . Impulses continue to be sent to wire NIA over contact 13 of bank 2.

At the end of the digit, relay Y releases during the interdigital pause and magnet SRM again operates over contact 13 of bank 4, wiper No. 4, $ss4$ front, $y2$ back, $p2$ back, $c1$ back, and when Y re-operates, magnet SRM releases and steps its wipers on to contact 14 .

The following digits of the message are distributed to wires NIB, NIC, NID, NIE and NIF, to which number indicators are connected in the same way, all the number indicators being held by ground connected to wire H. On the last digit of the message, the wipers of switch SR step on to contacts No. 23 on the first impulse and when Y releases and re-operates after the end of impulsing step on to contacts Nos. 24 .

The message ends after the last digit with tone which persists for the same period as an interdigital pause, but then ceases. This causes a discharge in tube T and relay C operates. Relay AX operates to front contacts $c1$ and at contacts $ax1$ operates relay F over contact No. 24 of bank 5. Relay F locks over front contacts $f2$, front contacts $zb4$, back contacts $ed4$.

Relay X releases after an interval, but its contacts $x2$ do not extinguish the discharge in the tube T since there is now no tone to oppose the bias applied to the control electrode. After an interval relay G releases, since its circuit is broken at contacts $x1$. At contacts $g1$, the circuits of relays S, SS (W if operated), Z and ZA are broken. Contacts $z4$ in changing over break the circuit of relay ZB, but hold relay F operated when contacts $zb4$ open. At contacts $f3$ the number indicators are held to display the message received by maintaining ground on wire H.

When relay S releases its contacts $s1$ and $s2$

remove the bias from the control electrode of tube T and contacts $g2$ disconnect relay C from the cathode and thus also remove the earth potential therefrom, and thus discharge in tube T is extinguished. Relay C releases.

Relay AX releases and contacts $ss3$ open the circuit of relay Y. Relay Y releases after an interval and completes a circuit for magnet SRM over wiper and commoned contacts of bank 1, $ss4$ back, $y2$ back, $p2$ back, $c1$ back. When relay Y reoperates its circuit being closed over $y1$ back, $ed3$ back, the wipers of switch SR step on to the home contact. Relay ED operates over $ss1$ back, lower winding of relay ED, home contact and wiper of bank 1, winding of stepping magnet SRM.

The circuit remains in this condition, with the last message received displayed upon the number indicator until current is again received over transformer TR. The changes previously described then take place. When impulses commence, the selector switch is stepped, as previously described. If the code signal first received be that for the station shown, relay Z operates as previously described and at contacts $z4$, breaks the holding circuit for relay F, and over contacts $f1$ back, $z3$ front the calling lamp CL is lit and at contacts $f3$ the holding circuit of the indicators is broken and they return to normal. The interpolated digit referred to above is of long enough duration to ensure this return to normal.

Should however a code for some other station be received, relay W operates, as previously described, and at contacts $w3$ maintains relay F operated. Thus the previous message received remains displayed until the code of the station shown be received, indicating that a further message is about to be received.

It will be clear from the above that the release and re-operation of Y takes place in an interdigital pause. Thus if an impulse fails to be properly received, this will be interpreted as an interdigital pause and the received code will appear to contain an additional train of impulses. If this takes place during the first part of the received code, i. e. the part selective of the station to receive the message, the selector switch will not receive the correct total number of impulses and there will be no operation of relay Z. Relay W will be operated and the code message will not be displayed. If an impulse is missing in the message part of the code and thus an additional digit be received, the operation is as follows:

At the end of the sixth digit, the wipers of SR are stepped from contact 23 to contact 24 . If now relay AX responds to a further received impulse, relay F is operated from $ax1$ front over contact 24 of bank 5, and locks over $f2$ front. At the end of this extra digit relay Y releases and completes a circuit for magnet SRM, contact 24 of bank 4, wiper 4 , $ss4$ front, $y2$ back, $p2$ back, $c1$ back, and when Y re-operates, SRM steps the wipers on to the home contact. At the end of the impulsing, relay AX responds as previously described, and contacts $ax1$ complete a circuit over bank 5 for relay ED. At contacts $ed4$, the holding circuit for relay F is broken and when the circuit returns to normal the indicators will also return to normal.

Relay Y provides a safeguard against an interdigital pause that is too long. For each digit of the message the switch SR takes two steps, and on the release and reoperation of Y during an interdigital pause the wipers are stepped on to

a contact connected to a different number indicator.

Thus the first digit of the message is received on contacts 12 and 13 and in the interdigital pause the switch is stepped to contact 14. If now relay Y releases a second time whilst the switch is on this contact, relay W operates over bank 4, ss4 front, y2 back, p2 back, c1 back and locks. Contacts w3 remove holding potential from the number indicators at wire H, which release if the message were intended for the station shown. Otherwise relay F remains operated to hold the indicator.

If the message is a digit short, release will not occur when the wipers are on contacts 24 and thus relay F will not be operated and the indicators will release when relay ZB releases.

A message may be broadcast to all stations by sending eleven impulses. This will cause the wipers to step to contacts 11 and relay Z will operate independently of the receipt of the individual code of the station shown. When relay Z is operated the indicator is released. Thus if the code of the station on the eleven impulses be received and impulsive then ceases without any message being sent the set up message is cancelled and the selector switch stepped to its home position over bank 1, by impulses from contacts y2.

Referring now to Fig. 2, this shows a somewhat simplified and improved version of the circuit of Fig. 1. The gas filled tube T has been replaced by a thermionic valve T1 and the impulse receiving relay C by an impulse receiving relay A. As in Fig. 1 when the circuit is seized by the receipt of alternating current relay A operates, but thereafter the receipt of impulses is denoted by the release of relay A.

When relay A operates, contacts a2 close the circuit of relay AX' which operates. Contacts a1 close in order to keep the grid circuit of valve T1 closed when relay X' operates. Contacts a3 close a circuit for relay X' which operates after about 40 ms. Contacts x1 close a circuit for relay G' which operates. Relay G' is slow releasing and remains operated throughout subsequent release periods of relay X'. Contacts x2 open a path in the grid circuit of the valve T1 parallel to that closed by contacts a1. Contacts g1 prepare a circuit for switch magnet SRM'. Contacts g3 prepare a circuit for relay W'. Contacts g4 close a circuit to wire BL to light a busy lamp. Contacts g2 complete a circuit for relay Y', over g2 front, r1 back, home contact and wiper of bank 5 of the selector switch SR, to positive.

Impulses consist of interruptions of alternating current and on such an interruption relay A releases. At its contacts a1 it opens the grid circuit of the valve T1, so that even if the received impulse is short, relay A cannot re-operate until relay X' has released. At contacts a2 a circuit is completed for switch magnet SRM' (negative, SRM', g1 front, w4 back, z7 back, a2 back, positive), which operates. At contacts a3 the circuit of relay X' is broken, but this relay does not close its back contacts until after about 40 milliseconds.

When relay X' has released and alternating current is again received over the line L, relay A re-operates and at contacts a2 breaks the circuit of magnet SRM' which releases and steps the wipers of the selector switch. The selector switch is thus stepped in response to the impulses. Relay Y' remains operated during a train of im-

pulses, its circuit being completed over g2 front and either a3 back or x1 back.

As in the case of the circuit of Fig. 1 relay Y' has time to release during an interdigital pause and relay W' is able to operate if the wiper 4 of the selector switch has come to rest on a contact other than that denoting the station code (negative, relay W', contact, wiper of bank 4, y1 back, ax2 front, positive), and locks over w3 front, g3 front, and positive. Relay W' at contacts w4 opens the circuit of magnet SRM' and further impulses will have no effect.

If the station code has been correctly received, the wipers reach contacts No. 11, relay Y' releases on the interdigital pause, and relay Z' operates (negative, relay Z', h3 back, contact No. 11 and wiper of bank 4, y1 back, ax2 front, positive). Relay Z' locks over z6 front, to g3 front and positive, and at contacts z1 connects positive to wire CL to light a calling lamp. At contact z2 a resistance in series with the holding magnets of the call indicator (connected to wire H) is short circuited. At z3 a circuit is prepared for the impulses to go to the number indicators. Contacts z7 change over the impulsive circuit so that magnet SRM' is no longer operated on each impulse. On the first impulse of the next series of impulses a circuit is completed for relay H (negative, lower winding of relay H, contact No. 11 and wiper of bank No. 3, z5 front, ax2 back, positive). The circuit for the holding magnets of the number indicator is broken by h1 and any existing message displayed thereon is cleared. Relay H remains operated in a circuit over its upper winding, wiper and contact No. 11 of bank No. 2, h1, positive.

When relay Y' releases at the end of the series of impulses, a circuit is completed for magnet SRM' over g1 front, w4 back, z7 front, h3 front, contact No. 11 and wiper of bank 4, y1 back, ax2 front, positive. When relay Y' re-operates this circuit is broken and the wipers of the switch step to contact No. 12, whereupon relay H releases and recloses at contacts h1 the circuit for the holding magnets of the number indicator.

When the first impulse of the next set of impulses is received it is repeated by contacts ax1 over w2 back, z3 front, wiper and contact of bank 1 to wire NIA. A circuit is completed from magnet SRM', over g1 front, w4 back, z7 front, contact No. 12 and wiper of bank 3, z5 front, ax2 back, positive. After the first impulse magnet SRM' de-energises and the wipers step to contact No. 13. Over this contact of bank 1 the impulses continue to go to the wire NIA.

At the end of the digit, relay Y' releases and closes a further circuit for magnet SRM' over wiper and contact No. 13 of bank 4 and when relay Y' operates again, the wipers step to contacts Nos. 14. As before succeeding digits are sent to the wires leading to the number indicator over pairs of contacts, the last digit being sent over contacts Nos. 22 and 23 of bank 1. When relay Y' releases at the end of this last digit, magnet SRM' is energised as before, but relays A and AX' remain operated. There is, however, a circuit to re-operate relay Y' over y2 back, r2 back, contact No. 23 and wiper of bank 5, positive. Relay Y' re-operates, whereupon magnet SRM' is de-energised and the wipers step to contacts Nos. 24.

The signalling now comes to an end and the alternating current ceases before relay Y' has time to release again so that relays A and AX' release. When relay AX releases a circuit is closed for relay R over h2 back, contact No. 24 and

wiper of bank 3 of the switch, $z'5$ front, $ax'2$ back, to positive. After an interval relay G' releases, and relay Y' also releases, but a circuit exists for relay Y' over $y'2$ back, contact No. 24 and wiper of bank to positive, and after an interval relay Y' re-operates. There is then a circuit to operate magnet SRM' over $g'1$ back, $y'2$ front and the same circuit as for relay Y' . After an interval relay Y' again releases and magnet SRM' steps its wipers to the home contact. Relay R releases and relay Y' also releases after an interval and the circuit returns to normal.

If the station code were not received and relay W' has been operated, the switch remains on contact No. 11 until impulsive ceases and until relay G' has released at the end of the message. When relay Y' releases a circuit exists for it over its own back contacts $y'2$ and contacts Nos. 11 to 22 of bank 5, so that relay Y' re-operates and operates magnet SRM' over $g'1$ back, $y'2$ front. Relay Y' continues to release and re-operate, operating and releasing magnet SRM' to step the wipers to contacts Nos. 23. In this position magnet SRM' operates over $g'1$ back, $y'2$ front, $r'2$ back, contact No. 23 and wiper of bank 5 and when relay Y' releases, the wipers step to contacts Nos. 24. Whilst the wipers are on contacts Nos. 12 to 23 the locking circuit of relay H is maintained over its upper winding, contacts and wiper of bank 2, $z'4$ back, $h'1$ front, positive. On contact No. 24 the locking circuit of relay H is maintained independently of contacts $z'4$. The wipers step from contacts Nos. 24 to the home contacts in the manner described above, where relay H still remains locked in a circuit over the wiper and contact of bank No. 2 but again including back contacts $z'4$.

What is claimed is:

1. Apparatus for receiving and regenerating electric impulses comprising an impulse responding relay, a second relay, means to cause the response of said second relay to be dependent upon said impulse responding relay, a circuit for said second relay including means to time the operation thereof, and means for maintaining said impulse responding relay in the condition caused by a received impulse until the completion of response of said second relay.

2. Apparatus as claimed in claim 1 and an electrical discharge device for controlling the operation of said impulse responding relay, and a circuit for controlling said discharge device controlled by the second relay.

3. Apparatus as claimed in claim 1, a normally inactive electrical discharge device for controlling the operation of said impulse responding relay, a circuit for operating said device by the impulses, and a circuit controlled by the second relay for maintaining said device operated.

4. Apparatus as claimed in claim 1, a normally inactive electrical gas discharge device having an anode, a cathode and a control electrode, an energizing circuit for said impulse responding relay connected to said cathode, a circuit for applying the impulses to the control electrode, and a circuit for the anode controlled by the second relay.

5. Apparatus as claimed in claim 1, a normally inactive electrical discharge tube having an anode a grid and a cathode, a circuit connecting the anode to said impulse responding relay, a circuit for applying the impulses to the grid, and a circuit for controlling the cathode controlled by the second relay.

6. Apparatus for receiving electric impulses and for timing a pause between trains of impulses comprising an impulse relay, a second relay, means to cause the response of said second relay, means to be dependent upon said impulse responding relay, a self-interrupting circuit for said second relay for timing the release and re-energisation of said second relay, means for releasing said second relay for self-interruption during a pause between trains of impulses, and means controlled by the release and re-operation of said relay to time said pause and discriminate between said pause and the cessation of impulsive.

7. Apparatus for receiving and regenerating electric impulses comprising an impulse responding relay, a second relay, means to cause the response of said second relay to be dependent upon said impulse responding relay, a circuit for said second relay including means to time the operation thereof, means for maintaining said impulse responding relay in the condition caused by a received impulse until the completion of response of said second relay, a selector switch, and means for causing the impulse responding relay to repeat the received impulses to said selector switch.

8. Apparatus as claimed in claim 7 in which a plurality of display devices are provided, means is provided to step said selector in response to the impulses repeated, and means responsive to impulses following a predetermined sequence of impulses to step said selector to connect said display devices for successive operation in accordance with the repeated impulses.

9. Apparatus as claimed in claim 7 in which a plurality of display devices are provided, means to step said selector switch in response to impulses means responsive to impulses following a predetermined sequence of impulses to step said selector successively to connect said display devices for operation in accordance with the repeated impulses, and means to hold said display devices actuated until said predetermined sequence of impulses is again received.

10. Apparatus as claimed in claim 7 in which a plurality of display devices are provided, means to step said selector switch in response to impulses, means responsive to impulses following three successive trains of impulses to step said selector to connect said display devices for successive operation in accordance with the repeated impulses.

11. Apparatus as claimed in claim 7 in which a plurality of display devices are provided, means to step said selector switch in response to impulses, means operative after the receipt of a plurality of trains of impulses to step said selector two steps for each impulse repeater successively to connect the display devices for operation in accordance with additional impulses received, means to hold said display devices actuated until said plurality of trains of impulses is again received, and means operative thereupon for releasing said display devices.

12. Apparatus for receiving and regenerating electric impulses comprising a line, a plurality of stations connected therewith, at each station a discharge tube having one electrode connected with said line to cause said tube to respond to impulses received on said line, an impulse responding relay connected to another electrode, a second relay, an energizing circuit for said second relay controlled by said impulse responding relay, means to time the operation of the second relay, means for maintaining said impulse re-

sponding relay in the condition caused by a received impulse until the completion of response of said second relay, a selector switch, a display device, means for repeating the received impulses, means for operating said selector switch in accordance with some of the repeated impulses for selecting one of said stations, and means responsive to additional impulses for operating the selector switch to connect the display device for operation by further repeated impulses.
